UNITED STATES PATENT OFFICE.

FRANK ROSENTHAL, OF NEW YORK, N. Y.

PROCESS OF MAKING THREAD.

No Drawing.

Application filed August 27, 1925. Serial No. 52,958.

My invention relates generally to the manufacture of ornamental fabric, and has particular reference to a method of producing such a fabric by the utilization of a 5 composition of the nature of viscose.

An object of the invention is to produce a fabric having ornamentations which simulate the ornamentations obtainable by the actual utilization of genuine silk thread.

10 A further object lies in producing such a fabric by a method which is extremely simple and inexpensive, reliable, requiring no particular skill, and productive of surprising and novel results.

15 Where I have attempted to produce ornamentations upon a fabric base by the deposit of a plastic mass thereon, I have found that the plastic masses hitherto employed by me have been of such a character that in order 20 to give the desired ornamental effect, the deposited material had to be treated either before or after the deposition thereof, as by flocking, so as to produce the desired result. More specifically, where the effect desired 25 was an ornamentation which would resemble the effect produced by the utilization of genuine silk thread, the material deposited, in general had to be treated with a coloring matter which would impart to the surface of such deposited material an appearance of silk.

Accordingly, another object of the present invention is to provide a method of producing a fabric of this nature, wherein the 35 necessity for such treatment has been eliminated, and wherein the material deposited will in and of itself and by virtue of its own inherent characteristics produce the desired effect.

40 More specifically, it is an object of the invention to produce a fabric of this character which will resemble the type of fabric which is produced by the utilization of silk thread which has been obtained from uncultivated silk worms.

Another object is to produce a fabric which will bear ornamentations of the nature and appearance of silk embroidery, without however encountering any of the 50 difficulties or expense generally involved in genuine embroidery work.

A feature of the invention lies in the direct deposition of a material like viscose in accordance with a predetermined plan, upon 55 a fabric or its constituent threads.

For the attainment of the foregoing ob-

jects and such other objects as may herein-after appear or be pointed out, I shall now describe several processes which are illustrative of possible modes of carrying out my invention.

It is a well-known fact that silk thread which is obtained from imperfect or freak cocoons, or from the cocoons of wild or uncultivated silk worms, will be irregular in 65 texture and will carry "nubs, or thickened portions, at frequent irregular intervals. These very imperfections, however, have been utilized to effect an irregular, yet pleasing, ornamentation upon fabric, by manufacturing the fabric of these imperfect threads.

One of the objects of my invention is the production of a thread which simulates this imperfection, and more particularly the production of a thread predeterminedly simulating these imperfections.

One method of carrying out my invention lies in directly depositing upon or causing to be associated with an already formed base 80 thread, preferably though not necessarily of silk or artificial silk or upon an artificial thread simultaneously with its formation, masses of viscose of pasty consistency, at regular or irregular intervals, and in accordance with a predetermined plan to simulate the imperfect threads hereinbefore referred to. Where the imitated nubs are associated with an already formed thread, the viscose is preferably prepared in the form of a pasty mass, and made available as required. Pre-determined quantities or gobs of the mass may be deposited upon the base thread at suitable irregular intervals, and the inherent characteristics of the viscose 85 will cause it to harden and to become part and parcel of the thread in such a manner that the resulting thread will be hardly distinguishable from the genuine product obtained from the uncultivated cocoons. The fabric is then woven in a well-known manner, and ornamentations will result which will be artistically irregular in accordance with the predetermined plan.

It will be obvious that a modification of this process will permit of the deposit of viscose masses at regular intervals, if desired, in accordance with any predetermined or desired artistic scheme, and the resulting fabric will have an unusual ornamental effect, in that it will appear to have been made from imperfect genuine silk threads,

yet bearing at the same time designs having certain features of regularity.

In order to carry out and fully attain the objects of my invention, I may control or vary the quantity of thread material thereby forming the irregularities, nubs, or thickened portions and I preferably, although not necessarily, do this in a predetermined manner so as more effectively to produce the new and desired results. This controlled or predeterminedly controlled varying of the quantity of material may be accomplished in many ways. As an example, I may obtain a surging action by providing for the irregular operation of the pump acting to force the viscose material through the dies, whereby the viscose material is more or less rapidly forced through said dies at the irregular impulse strokes of the pump. This has been found to effectively produce the intended results as the irregular impulses may readily be given to the pump through the use of cam arrangements. Such an arrangement would, moreover, lend itself to any desired predetermined control as the cam faces can be contoured to give any predetermined or controlled irregularities. As a further example of an efficient manner of carrying my invention into effect, I may associate with the main pump forcing the viscose material through the dies, an auxiliary pump which may vary the pressure at the extruding orifices of the dies, or the amount of material passing therethrough in a given time, or both, and thus again fully effectuate my present invention.

Another method of carrying out my invention is the result of carrying the basic idea a step further. Instead of depositing the viscose at regular intervals upon a base thread and thereupon weaving the fabric, it is possible and often preferable to deposit the viscose in accordance with a predetermined plan of ornamentation upon a finished base fabric, that is, upon a fabric already woven. In accordance with this method, a base fabric, such as cotton, may be rendered ornamental by directly depositing viscose thereon in predetermined quantities and masses and along predetermined lines or areas, and by virtue of the fact that the deposits will become part and parcel of the base fabric, the result will be one of a fabric bearing silk ornamentations. In accordance with this method, the material which has been selected as a base, either silk or non-silk, as desired, is suitably laid out and may if desired be stenciled or similarly imprinted in a temporary manner with the particular design in contemplation, although this preliminary outlining of the design is not an essential step. Viscose is then prepared in the same manner as hereinbefore described, namely, in the form of

a pasty mass, and is made suitably available in any preferred manner. One method of rendering the viscose available for this purpose is to insert it into a plurality of tubes having outlet openings of varied sizes and configurations, whereby viscose streams of desired thicknesses or mass may be expelled by pressure upon the tubes. The tubes are then manipulated in any desired or preferred manner as in the manner of pencils, and the viscose is deposited directly upon the base fabric along lines or areas dependent in size, length, and configuration upon the particular ornamentation which has been decided upon. Thereupon the deposited material is allowed to dry, whereby it will become closely associated with the fabric in a manner to become part and parcel thereof. A deposition process similar to printing may also be employed.

In cases where the deposits have been made along lines simulating embroidery, the resulting ornamentation will not only resemble genuine embroidery, but will consist of actual artificial silk integrally associated with the fabric as though genuinely produced by embroidery processes. Accordingly, the advantages of silk embroidery work are obtained without any of its disadvantages having been encountered.

Although not essential, it will be obvious that the viscose may be suitably colored before application, or that suitable coloring matter in the form of a deposited powder or the like may be added to it after it has been applied to the fabric.

It will be obvious that various changes in the details as herein described for the purpose of explaining the nature of my invention may be made by those skilled in the art without departing from the spirit and scope of the invention as expressed in the appended claims, and it is therefore intended that these details be interpreted as illustrative and not in a limiting sense.

It will be observed that in the specification and claims the term "thread material" is intended to apply to the material forming the thread, whether plastic or otherwise, or to the subsequently formed thread.

The irregularities herein referred to have been described as simulating those formed by the uncultivated silk worm cocoon. It will be understood, however, that such need not be the case.

In the claims where I make reference to forming a fibre or thread with irregularities thereon by associating with the thread materials such irregularities by a "predetermined" controlled or varying quantity of material, I mean to include thereby such additions or variations as will give an irregular or ornamental effect in accordance with some predetermined scheme or plan to obtain effects of definite irregularity, and not

merely accidental, such as might be caused by an improper handling of the mechanism or coagulating baths affecting merely in an undesired manner the filament or thread for 5 purposes of weaving, knitting or otherwise handling the filament or thread for forming a fabric.

Having thus described my invention and illustrated its use, what I claim as new and 10 desire to secure by Letters Patent, is:

1. The herein described process of making thread for ornamental fabric, which consists in depositing viscose in substantial relief upon a base material in the form of 15 a thread in accordance with a predetermined plan of treatment or relief ornamentation.

2. The herein described process of making threads to be employed in the manufacture 20 of fabrics to simulate fabrics made from silk threads obtained from uncultivated silk worm cocoons with irregularities thereon, said process consisting of adding to 25 the thread material such irregularities by a controlled varying quantity of material.

3. The herein described process of making threads to be employed in the manufacture 30 of fabrics to simulate fabrics made from silk threads obtained from uncultivated silk worm cocoons with irregularities thereon, said process consisting of adding to 35 the thread material nubs by a controlled varying quantity of material.

4. The herein described process of making threads to be employed in the manufacture 40 of fabrics to simulate fabrics made from silk threads obtained from uncultivated silk worm cocoons, with irregularities thereon, said process consisting of associating 45 viscose nubs with the thread.

5. The herein described process of making a thread to be employed in the production 50 of a fabric to simulate that made from silk threads obtained from the irregularly formed thread of the uncultivated silk worm cocoon, said process including the simultaneous formation of a thread from viscose and the association therewith of irregularities by a controlled varying quantity of material.

6. The herein described process of making a thread to be employed in the production 55 of a fabric to simulate that made from

silk threads obtained from the irregularly formed thread of the uncultivated silk 55 worm cocoon, said process including the simultaneous formation of a thread from viscose and the association therewith of irregularities by a controlled varying quantity of material. 60

7. The herein described process of making threads to be employed in the manufacture 65 of fabrics to simulate fabrics made from silk threads obtained from uncultivated silkworm cocoons, with irregularities thereon, said process consisting of associating predetermined controlled quantities of viscose material forming nubs with the thread while the threads are being formed.

8. In the herein described process of 70 making ornamental fabric, the step which consists in forming a fibre or thread from viscose and varying the quantity of material forming the body thereof in a predeterminedly controlled manner so as to cause 75 said thread to have an irregular exterior surface.

9. The herein described process of making threads to be employed in the manufacture 80 of fabrics to simulate fabrics made from silk threads obtained from uncultivated silk worm cocoons with irregularities thereon, said process consisting of associating 85 such irregularities with the thread by a controlled varying quantity of material while the threads are being formed.

10. A fabric formed in simulation of one made from irregularly formed threads obtained from uncultivated silk worm cocoons, said fabric having irregularities in 90 the threads formed artificially by associating a controlled varying quantity of material with the threads thereof.

11. As a new article of manufacture, a thread having irregularities in its contour 95 to simulate the thread produced from silk obtained from uncultivated, wild or freak silk worm cocoons, said thread having its irregularities in contour resulting from predeterminedly controlled variations in the 100 quantity of material forming the body thereof at varying points in its length.

In witness whereof, I have signed and sealed this specification.

FRANK ROSENTHAL.
